UNITED STATES PATENT OFFICE.

WILLIAM J. CAMPBELL, OF GLENS FALLS, NEW YORK, ASSIGNOR TO INTERNATIONAL PAPER COMPANY, OF NEW YORK, N. Y., A CORPORATION OF NEW JERSEY.

FLOW-EQUALIZING DISTRIBUTER FOR PAPER-MACHINES.

1,201,693.

Specification of Letters Patent. Patented Oct. 17, 1916.

Application filed April 21, 1910. Serial No. 556,667.

To all whom it may concern:

Be it known that I, WILLIAM J. CAMPBELL, a citizen of the United States, residing at Glens Falls, county of Warren, State of New

5 York, have invented certain new and useful Improvements in Flow-Equalizing Distributors for Paper-Machines; and I do hereby declare the following to be a full, clear, and exact description of the invention, such as 10 will enable others skilled in the art to which it appertains to make and use the same.

My invention relates to certain new and useful improvements in flow-equalizing distributors for paper machines and particularly to means, coöoperating with the usual slice-bar, for distributing the stock to better advantage as it enters upon the Fourdrinier wire-screen, where the felting of the fibers of the wood pulp or the like takes place.

20 To this end, the invention consists in providing a flow-distributer having a series of pendant projections or teeth extending down into the stream of stock, preferably to near the bottom thereof. The effect is to cause a 25 series of small eddies across the flow of the stock, thereby assisting in the final felting of the fiber by giving them, as they pass under the distributer, a tendency to cross and interlace with each other. This prefer- 30 ably takes place just before they reach the usual slice-bar, which has the customary function of determining the level of the stock, as it enters upon the wire screen of the machine, and to hold back objectionable 35 floating substances and the like.

My invention has the additional purpose of causing a more uniform distribution of the stock across the entire width of the stream, by breaking up the stronger currents 40 that may exist at any place in the stream, and equalizing to a greater degree the rate of speed with which the stock as a whole passes under the usual slice-bar, and onto the screen-wire.

45 In the accompanying drawing, Figure 1 represents, partly broken away at its middle portion, the preferred form or embodiment of my invention. Fig. 2 represents a top plan view thereof. Fig. 3 represents a 50 section taken on a plane indicated by the line 3—3 of Fig. 1. Fig. 4 represents a section taken on a plane indicated by the line 4—4 of Fig. 1; and Fig. 5 represents, in section, the application of my invention to a 55 paper machine.

Similar letters of reference indicate similar parts throughout the several views.

Referring to the drawing, it will be noted that, in the specific embodiment of the invention therein illustrated, the distributer is 60 made in two parts *a*, adjustable longitudinally, so as to accommodate the distributer to the width of the particular paper machine with which it is to be employed. To this end, the sections *a* are provided with 65 longitudinal flanges *b* at their upper edges, these flanges coöoperating with suitable clips *c* and filler pieces *d*, whereby, through the instrumentality of the set screw *e* and lock-nut *f*, the desired longitudinal adjustment 70 may be obtained.

At their outer ends, each section *a* is provided with a bracket lug *g*, carrying a set screw *h* and lock-nut *i*, or some similar connection for releasably attaching the distributer to any upright of the machine, as for instance, the upright *m* shown in Fig. 5.

In Fig. 5, I have shown, more or less in general outline, the preferred relationship of the distributer to the usual slice-bar *n*, 80 carried by the deckle-frame *s*, and located, as is customary in paper machines, immediately in advance of the place where the stock flows upon the Fourdrinier wire screen, the stock being fed from the flow box 85 *t*, or its equivalent.

As hereinbefore indicated, the downward projections or teeth of the distributer, indicated by the letter *v*, are intended to dip well down into the flowing stream of wood pulp 90 or other paper stock, preferably to near the bottom thereof. In this way, there is formed across the entire width of the flowing stream of stock a series of small eddies at the rear of the teeth or projections *v*, these eddies 95 tending to cause the fibers in the stock to cross or intersect each other to a greater or less degree, thereby presenting the stock to better advantage to the felting action of the shaking Fourdrinier screen, and substantially equalizing the rate of flow of the stock, 100 by breaking up any stronger currents that may exist at any part thereof, before the stream enters upon the screen-wire.

Having thus described my invention, what I claim is:—

1. In a paper making machine, means for causing a succession of small eddies across the stream of pulp as it is being supplied to the machine, said means being stationary with respect to the said stream; substantially as described.
2. In a paper making machine, a series of teeth spaced apart and extending transversely of the pulp stream and dipping below its surface as it is being supplied to the machine, said teeth being stationary with respect to said stream; substantially as described.
3. In a paper making machine, the combination of a shaking screen, a slice bar near the receiving end thereof, and a series of teeth stationary with respect to said slice bar and positioned slightly in advance thereof, said teeth being spaced apart and extending transversely of the pulp stream and dipping below the surface as it is being supplied to the screen, thereby equalizing the flow and aiding the felting on the screen, substantially as described.
4. In a paper making machine, the combination of a shaking screen and a distributing and eddying device positioned near the receiving end of said screen, said device consisting of a bar made in overlapping sections adjustable longitudinally with respect to each other, said sections having each a series of teeth spaced apart and dipping into the pulp stream and there held stationary to equalize the flow and produce eddies aiding in the felting of the pulp on the shaking screen, substantially as described.

In testimony whereof I affix my signature, in presence of two witnesses.

WILLIAM J. CAMPBELL.
